CLAIM

The ornamental design for a medicine administration device, as shown and described.

DESCRIPTION

FIG. 1 is a perspective 1 view of a first embodiment of a medicine administration device showing my new design;

FIG. 2 is a perspective 2 view thereof;

FIG. 3 is a front view thereof;

FIG. 4 is a back view thereof;

FIG. 5 is a top view thereof;

FIG. 6 is a bottom view thereof;

FIG. 7 is a right view thereof;

FIG. 8 is a sectional view along the line shown in FIG. 4 thereof;

FIG. 9 is a perspective view thereof showing a state in which the stopper was removed;

FIG. 10 is a front view thereof showing a state in which the stopper was removed;

FIG. 11 is another view of FIG. 8, but shown in a usage state;

FIG. 12 is another view of FIG. 11 shown in a usage state, but in a compressed position;

FIG. 13 is a perspective view of a second embodiment of a medicine administration device showing my new design;

FIG. 14 is a front view thereof;

FIG. 15 is a back view thereof;

FIG. 16 is a top view thereof;

FIG. 17 is a bottom view thereof;

FIG. 18 is a right view thereof;

FIG. 19 is a sectional view along the line shown in FIG. 15 thereof;

FIG. 20 is another view of FIG. 19, but shown in a usage state;

(Continued)

FIG. 21 is another view of FIG. 20 shown in a usage state, but in a compressed position;
 FIG. 22 is a perspective 1 view of a third embodiment of a medicine administration device showing my new design;
 FIG. 23 is a perspective 2 view thereof;
 FIG. 24 is a front view thereof;
 FIG. 25 is a back view thereof;
 FIG. 26 is a top view thereof;
 FIG. 27 is a bottom view thereof;
 FIG. 28 is a right view thereof;
 FIG. 29 is a sectional view along the line shown in FIG. 25 thereof;
 FIG. 30 is a perspective view thereof showing a state in which the stopper was removed;
 FIG. 31 is a front view thereof showing a state in which the stopper was removed;
 FIG. 32 is another view of FIG. 29, but shown in a usage state; and,
 FIG. 33 is another view of FIG. 32 shown in a usage state, but in a compressed position.
 The broken lines in the drawings illustrate portions of the medicine administration device and form no part of the claimed design.
